UNITED STATES PATENT OFFICE.

GUSTAVE DELAGE, OF PARIS, FRANCE, ASSIGNOR TO SOCIÉTÉ ANONYME NIEUPORT ASTRA, OF ISSY-LES-MOULINEAUX, FRANCE, A FRENCH COMPANY.

METALLIC PROPELLER WITH ADJUSTABLE PITCH AND DETACHABLE BLADES.

Application filed March 20, 1925, Serial No. 17,048, and in France May 30, 1924.

The present invention has for object a metallic propeller, the detachable blades of which are formed by cylindrical surfaces without torsion. This propeller is more particularly characterized in that the blades are provided, on their straight section, with a hooking heel-piece engaging into a corresponding diametral mortice provided on one of the cheeks of the hub assembling them; the relative positions of the blades being defined by means of rings having concentric or eccentric surfaces which fit on an axial trunnion of the hub and engage into corresponding recesses provided on the hooking edges of the blades.

In the accompanying drawings and by way of example:

Figs. 1 and 2 illustrate, in perspective one of the blades of the propeller and one of the cheeks of the hub.

Fig. 3 is a vertical section showing the assemblage of the blades with the cheeks of the hub.

Figs. 4 and 5 are an elevation and plan view showing how the pitch of the blades can be modified by altering the shape of the ring keying them relatively to the hub.

As indicated in the foregoing, the metallic propeller is constituted by two cylindrical blades *a*, that is to say these blades have rectilinear generatrices and semi-circular directrices. The straight sections, adapted to be juxtaposed, are respectively provided with a hooking heel-piece *b*. In the case illustrated by Fig. 1, this heel-piece *b* is directed towards the extrados of the blade, but it might project on the intrados or form the horizontal branch of a $\perp$ at the corresponding portion of the blade *a*.

These blades *a* are assembled together and connected to the shaft which must drive them in rotation by a hub. This hub is constituted by two cheeks *c*, *d*, both having on either one or the other, a diametral mortice *e* capable of receiving the hooking heel-piece *b* of the blades *a*. Their faces are so shaped as to fit against the corresponding faces of the blades *a* which they embrace between them.

The inner cheek *c* has an axial trunnion *e* on which is centered the other cheek *d* and the blades *a* have, on their edges provided with the hooking heel-pieces *b*, cylindrical recesses *f* the radius of which is greater than that of the trunnion *e*. In the

case illustrated, a nut *g* secured on the trunnion *e* completes the assemblage.

For relatively securing the blades *a*, on the trunnion *e* is fitted a ring-shaped key *h* the outer surface of which engages with the recesses *f* provided in the two blades *a*.

In the constructional modification of Fig. 4, the outer and inner surfaces of the key *h* are concentric. The form of construction of Fig. 5 shows that by providing a ring *h* the outer walls of which are out of center relatively to its bore, it is possible to produce a relative angular displacement of the blades *a*, this determining a variation of the angle of incidence, or, in other words, of the pitch.

It is obvious that for a determined type of propeller to the cylindrical recesses *f* formed in the edges of the blades *a* there might be substituted recesses capable of adapting themselves to elliptical keys the axis of symmetry of which is in the bearing plane of the hooking ledges *b* of the said blades.

In the same way, the outer surfaces of the keys *h* might not be cylindrical surfaces. They might, for instance, also comprise tenons fitting in corresponding mortices provided in the blades *a*.

To sum up, in the system, the blades *a* are rendered rigid by their hooking heel-pieces *b* with the hub, the central key *h* which supports the latter fixing the relative positions of the blades *a*.

The diameter of the propeller might also be varied by forming, on the cheek or cheeks of the hub, several mortices *e*, or by giving to the mortice *e*, a width greater than that of the two heel-pieces *b*. The placing in position of the latter would then be effected by means of intermediate wedges.

What I claim as my invention, and desire to secure by Letters Patent is:—

1. In a metallic propeller for aeronautics, the arrangement in alignment with each other, of cylindrical blades,—projecting heel-pieces provided on the corresponding straight sections of the said blades,—and means for connecting together the said heel-pieces and the blades.

2. In a metallic propeller for aeronautics, the arrangement, in alignment with each other, of cylindrical blades,—heel-pieces provided on the corresponding straight sections of the said blades and projecting rela-

tively to their outer cylindrical surface,—an outer cheek having a cylindrical concave surface fitting on the outer cylindrical surface of the blades,—grooves in the said cylindrical concave surface for receiving the heel-pieces of the blades.

3. In a metallic propeller for aeronautics, the arrangement, in alignment with each other, of cylindrical blades,—heel-pieces provided on the corresponding straight sections of the said blades and projecting relatively to their outer cylindrical surface,—an outer cheek having a cylindrical concave surface fitting on the outer cylindrical surface of the blades, grooves in the said cylindrical concave surface for receiving the heel-pieces of the blades, an inner cheek,—a convex cylindrical surface, fitting on the outer cylindrical surface of the blades,—means for assembling together the said cheeks constituting the hub.
4. In a metallic propeller for aeronautics, the arrangement, in alignment with each other, of cylindrical blades,—heel-pieces provided on the corresponding straight sections of the said blades and projecting relatively to their outer cylindrical surface,—an outer cheek having a cylindrical concave surface fitting on the outer cylindrical surface of the blades,—grooves in the said cylindrical concave surface for receiving the heel-pieces of the blades,—an inner cheek,—a convex cylindrical surface, fitting on the outer cylindrical surface of the blades,—an axis rigid with the inner cheek for centering the outer cheek and securing it,—circular notches provided at the base of the blades for permitting the passage of the said assembling axis.
5. In a metallic propeller for aeronautics, the arrangement, in alignment with each other, of cylindrical blades,—heel-pieces provided on the corresponding straight sections of the said blades and projecting relatively to their outer cylindrical surface,—an outer cheek having a cylindrical concave surface fitting on the outer cylindrical surface of the blades,—grooves in the said cylindrical concave surface for receiving the heel-pieces of the blades,—an inner cheek,—a convex cylindrical surface, fitting on the outer cylindrical surface of the blades,—an axis rigid with the inner cheek for centering the outer cheek and securing it,—circular notches provided at the base of the blades for permitting the passage of the said assembling axis.

tively to their outer cylindrical surface,—an outer cheek having a cylindrical concave surface fitting on the outer cylindrical surface of the blades,—grooves in the said cylindrical concave surface for receiving the heel-pieces of the blades,—an inner cheek,—a convex cylindrical surface, fitting on the outer cylindrical surface of the blades,—an axis rigid with the inner cheek for centering the outer cheek and securing it,—circular notches provided at the base of the blades for permitting the passage of the said assembling axis,—the diameter of these notches being greater than of the axis rendering the cheeks rigid together,—and means for centering the blades relatively to the said axis.

6. In a metallic propeller for aeronautics, the arrangement, in alignment with each other, of cylindrical blades,—heel-pieces provided on the corresponding straight sections of the said blades and projecting relatively to their outer cylindrical surface,—an outer cheek having a cylindrical concave surface fitting on the outer cylindrical surface of the blades,—grooves in the said cylindrical concave surface for receiving the heel-pieces of the blades,—an inner cheek,—a convex cylindrical surface, fitting on the outer cylindrical surface of the blades,—an axis rigid with the inner cheek for centering the outer cheek and securing it,—circular notches provided at the base of the blades for permitting the passage of the said assembling axis, the diameter of these notches being greater than that of the axis rendering the cheeks rigid together,—cams fitting between the said axis and the notches of the blades for effecting the adjustment of the pitch of the latter.

In testimony whereof I have signed my name to this specification.

GUSTAVE DELAGE.
